(57) **CLAIM**

We claim the ornamental design for a button assembly for rearview assembly, as shown and described.

DESCRIPTION

FIG. 1 is a bottom front perspective view of a button assembly for a rearview assembly of the present disclosure; FIG. 2 is a bottom rear perspective view of the button assembly of FIG. 1;

FIG. 3 is a front elevational view of the button assembly of FIG. 1;

FIG. 4 is a rear elevational view of the button assembly of FIG. 1;

FIG. 5 is a first side elevational view of the button assembly of FIG. 1;

FIG. 6 is a second side elevational view of the button assembly of FIG. 1; and,

FIG. 7 is a bottom plan view of the button assembly of FIG. 1.

Broken lines are environmental only and form no part of the claimed design.
